[57] CLAIM

The ornamental design for a block sliding game, as shown and described.

DESCRIPTION

FIG. 1 is a front elevational view of a block sliding game showing my new design, the legible matter on the inside of the cover shown in broken lines for illustrative purposes only;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is an isometric view thereof.
